(57) **CLAIM**

We claim the ornamental design for a cordless hand scanner, as shown and described.

DESCRIPTION

FIG. 1 is a perspective view of a cordless hand scanner, showing our new design;

FIG. 2 is a front view thereof;

FIG. 3 is a top view thereof;

FIG. 4 is a left side view thereof;

FIG. 5 is a bottom view thereof;

FIG. 6 is a right side view thereof; and,

FIG. 7 is a rear view thereof.

Dashed lines in the figures are for illustrative purposes only and form no part of the claimed cordless hand scanner.
